UNITED STATES PATENT OFFICE.

JOHN DAY, OF NEW YORK, N. Y., ASSIGNOR OF ONE-HALF TO THE TURNER & SEYMOUR MANUFACTURING COMPANY, OF TORRINGTON, CONNECTICUT.

CURTAIN-ROD AND BRACKET.

SPECIFICATION forming part of Letters Patent No. 502,659, dated August 1, 1893.

Application filed September 24, 1892. Serial No. 446,773. (No model.)

To all whom it may concern:

Be it known that I, JOHN DAY, a citizen of the United States, residing in the city, county, and State of New York, have invented a new 5 and useful Improvement in Curtain-Rods and Brackets, of which the following is a full, clear, and exact description, reference being had to the accompanying drawings, forming part thereof.

10 My invention relates to curtain-rods and brackets and consists in the novel arrangement and combination of parts hereinafter described and specifically pointed out in the claim.

15 The object of my invention is to provide an improved curtain-rod and bracket which can be readily put in position and taken down and is equally adapted to be placed upon the inside or outside of framing (that is,

20 between the window or door-frames, or on the outside thereof) or at any angle thereon, whereby the necessity of using different pieces or brackets for inside and outside of the framing, as heretofore, is obviated.

25 In the drawings,—Figure 1 is a top view, partly in section, showing my improved curtain-rods and brackets applied to the inside of the framing. Fig. 2 is a top view, partly in section, of my rod and bracket applied to

30 the outside of the framing. Fig. 3 is a front view of the same. Fig. 4 is an end view of a rod in place on brackets in the position which they occupied when placed on the outside of a frame; and Fig. 5 is a view, partly in section, showing rounded or spherical part on the curtain rod, instead of on the brackets, and a co-operating socket bracket in line with the rod, instead of at right angles thereto.

35 A represents a curtain rod, which may or 40 may not be extensible, and in each end of which, in the preferred construction, is formed a socket *a*, which is substantially spherical. This socket is open at the end, and at one side, as shown at *a'* (Fig. 4). The 45 bracket *B* has two spring arms *b*, extending from a base preferably formed integral with the arms *b*, at the outer ends of which are

formed buttons, or projections *b'*, preferably of semi-spherical form.

When it is desired to put my improved 50 rods and brackets into use, if the rod to be used is extensible, the brackets are first secured to either the inside or outside of the frame, and the sockets *a*, of the rod *A*, are slipped over the buttons *b'* on the elastic arms 55 *b*. In this act the arms are first pressed sufficiently close together to allow the opening on the end of the rod to pass over the buttons *b'*, after which said buttons will separate in the sockets. If the rod to be used is not 60 extensible one bracket may be secured in place, and end of the rod connected thereto; then the second bracket should be connected to the opposite end of the rod, before said second bracket is secured in place. 65

It will be seen that by the construction described a ball and socket joint having an elastic member is provided, and that the members of the joint or the rod and bracket on which the members are formed are adapt- 70 ed to be connected in line with each other or at different angles, and the construction is such as to allow of the parts being readily attached to and detached from one another since they are held together solely by spring 75 pressure or friction. By employing this form of joint the bracket member may be either on the inside or outside of the supporting frame, as above indicated.

There are modifications in detail of con- 80 struction which I may make without departing from the spirit of my invention, such as making the balls or spherical enlargements on the ends of rod *A*, adapted to be held within the cup shaped ends *b'*, on the spring 85 arms *b* of brackets *B*, in Fig. 5. While it is preferred to make each bracket of a single piece, this is not essential.

Having described my invention, what I claim, and desire to secure by Letters Patent, 90 is—

The combination of two brackets, having bases adapted to be connected to the inside or outside of a window or similar frame, the

brackets having spring arms terminating in rounded parts b' , a curtain rod having at each end a corresponding part a , one set of said parts (that is the rounded parts on the brackets, or the corresponding parts on the curtain rod) being balls, and the other set being sockets—said sockets being cut away at one side, and being open at the ends, so

that the brackets may stand at an angle with the rod, or in line with it, substantially as described.

JOHN DAY.
